UNITED STATES PATENT OFFICE

GEORGE TRAUTVETTER, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA

PRESSED METAL DOOR

Application filed January 17, 1930. Serial No. 421,374.

My invention relates to doors for vehicle bodies, and more particularly to doors adapted to be fabricated out of pressed metal.

It is an object of my invention to provide a door of this class which is simple in construction, easy of assembly, and light in weight, and at the same time most strong and durable.

It is a further object of my invention to provide a door of this class having a simplified construction around the window opening therein, which permits the use therewith of the usual removable window moulding at its inner side.

15 These and other objects and advantages are attained by the novel construction shown in a preferred form in the attached drawings, and described in detail in the following specification.

20 In the drawings,

Fig. 1 represents in a perspective view, as seen from the inside, and outer panel stamping according to the invention.

Fig. 2 represents fragmentary views of 25 said outer panel stamping as viewed from the outside, parts being shown in section to show the construction around the window opening.

Fig. 4 represents in a perspective view, 30 as seen from the outside, an inner panel stamping according to the invention.

Fig. 5 represents in perspective, as seen from the outside, a half of the inner panel stamping as viewed from the inside, and 35 showing a central longitudinal section thereof.

Fig. 6 represents a similar view of the inner panel stamping, with parts assembled therewith, as viewed in this case from the 40 inside.

Fig. 7 represents a perspective view of one-half of the assembled door, and showing a central longitudinal section thereof.

45 Figs. 8 and 9 are fragmentary perspective views, parts being in section, showing the structure at the lower corners, respectively, of the window opening.

Figs. 10, 11 and 12 are enlarged sectional 50 details of the construction at the jamb side,

the top, and the hinge side of the window opening.

The door of the invention is constructed in the main of outer and inner panel stampings designated generally by the reference numerals 10 and 11.

The outer panel stamping may comprise, as shown in Fig. 1, a unitary stamping forming the outer face of the door provided at its outer edges with laterally extending flanges 12. At the window opening it is formed with a suitably contoured inwardly extending flange 13 forming the moulding. Adjacent the plane of the window, but spaced therefrom to permit the free vertical movement of the sliding window panel, the flange 13 is formed with the outwardly extending flanges 14 directed toward the outer margins of the panel and forming, at sides and top, the outer wall of the glass run channel. At the bottom, the flange 14 is inclined outwardly toward the body of the panel in a usual manner.

At sides and top the flanges 14 are extended inwardly by relatively wide extension flanges 15 extending at substantially right angles to the plane of the panel and forming the bottom of the glass run channels. At the base of the glass run channel these extensions are formed with spaced offset portions 16 for a purpose to be presently described.

The inner panel stamping may comprise the main body portion substantially in the inner plane of the door and against which the upholstery may be applied and the continuous outwardly extending flange 17 forming the jamb rail portion of the door. At the lock side of the door this jamb rail portion is formed of the usual stepped construction, as indicated at 18. A slight offset, as 19, may also be provided at the top for stiffening and strengthening the door structure.

At the sides and top the inner margin of the jamb rail portion 17 of the door is reversely bent on a smoothly rounded curve at 20, forming a marginal flange 21 extending outwardly substantially in the plane of the glass run channel of the completed door, and of a length to overlap the edge of the in-

wardly extending flange 15 of the outer panel stamping in the final assembly.

At the bottom of the window opening the inner panel is formed with a horizontal outwardly extending flange 22, the outer edge of which is bent downwardly to form the edge flange 23.

At the hinge side the inner panel is preferably reinforced by a reinforcing strip 24 of heavier gauge than the metal of the panel to make a secure anchorage for the hinges.

The downward extensions 25 and 26 of the glass run channels are also secured to the jamb face portions 17 of the inner panel prior to the assembly with the outer panel.

The inner and outer panel stampings are assembled in their outer margins in the usual manner by crimping the outer marginal flanges 12 of the outer panel stamping over the outer marginal door overlap flange 27 of the inner panel stamping, from the dotted line position shown in Fig. 7 to the full line position, and additionally by spot welding these flanges together in the door overlap.

When so assembled the inwardly extending flange 15 of the outer panel and the outwardly extending flange 21 of the outer and inner panels at the sides and top of the window opening overlap along their edge portions in a plane substantially the transverse plane of the bottom of the glass run channel, and they are preferably secured together at spaced points by tack welds, as indicated at 35 28.

The offset portions 16 of the flanges 15 of the outer panel stamping lie against the transverse jamb rail portions 17 or where an inner reinforce is employed as at the hinge rail, against the reinforce jamb rail portion, and are rigidly secured thereto by spot welding, as indicated, at 29.

By this construction, it will be noted that a very strong box-section rail structure is provided at the sides and top of the window opening, and one which permits a smooth and pleasing finish both on the inside and outside of the door. The reversely bent flange 21 of the inner panel is braced to the outer transverse jamb rail portion 17 through its connection with the edge of the flange 15 of the outer panel and the connection of the latter through the offsets 16 with the jamb rail portion 17, at both the sides and top of the window opening.

This construction provides a strong seat for the securement of the inner removable moulding, not shown, and by providing means whereby the window panel may be inserted in the door from the inside and not from the top, it avoids the weakening of the top rail of the door by a slot for the removal of the window. Also, the formation of the inner and outer panel stampings around the window opening in the manner

described can be accomplished by relatively few simple die operations.

What I claim is:

1. An outer panel for vehicle doors comprising a unitary stamping having a window opening formed therein, said panel being extended inwardly at the window opening to form moulding, and then flanged in the plane of the panel and transversely to form the outer side and bottom of a glass run channel, the transversely flanged portion being formed with spaced offsets for securing it to the door rail.

2. In a window rail construction, a metal rail built up of inner and outer stampings, the inner stamping having a transverse web portion forming the jamb portion of the door and its inner edge reversely bent, the reversely bent portion being spaced from the transverse web portion, the outer panel stamping being formed along one margin of angular form to provide the outer side and bottom of a glass run channel and flanged along its other margin to secure it to the outer margin of the inner stamping, the portion forming the bottom of the glass run being offset outwardly at spaced points and secured to the transverse web portion of the inner stamping, and secured along its margin to the reversely bent portion of the inner panel.

3. In combination, in a door structure, a unitary inner panel stamping extending about a window opening and having a continuous unbroken transversely extending jamb rail portion at the sides and top of said opening, the inner margin of said jamb rail portion being reversely bent outwardly at substantially right angles to the plane of the door, a removable window molding on the inner panel, and an outer panel extending about said opening and having an integral inner marginal portion extending inwardly beyond said inner panel margin in the plane of the door whereby a window may only be received between said panels in said opening laterally to the plane of the door and held in place by said removable window molding on the inner panel.

4. A pressed metal vehicle door having a window opening comprising inner and outer panel stampings flanged and secured together in their outer margins, the inner stamping being transversely extended to form the jamb face portions of the door and having its margin at the window opening reversely bent in spaced relation to the jamb face portion thereof, the outer panel being extended inwardly at the sides and top of the window opening in offset relation to said reversely bent portion of the inner panel but formed along its margin with an angle portion forming the outer side and bottom of a glass run channel, the inner margin of said angular portion being secured to the reversely bent portion of the inner panel and arranged in

substantially the same transverse plane and being provided with offset portion through which it is secured to the jamb face portions of the inner stamping.

5 In testimony whereof I hereunto affix my signature.

GEORGE TRAUTVETTER.
